UNITED STATES PATENT OFFICE.

FERDINAND A. RAFFEL, OF CLEVELAND, OHIO, ASSIGNEE TO THE SANDS MANUFACTURING COMPANY, OF CLEVELAND, OHIO, A CORPORATION OF OHIO.

HYDROCARBON-LAMP.

1,887,620.

Specification of Letters Patent. Patented Apr. 20, 1920.

Application filed September 6, 1919. Serial No. 322,063.

To all whom it may concern:

Be it known that I, FERDINAND A. RAFFEL, a citizen of the United States, residing at Cleveland, in the county of Cuyahoga and 5 State of Ohio, have invented certain new and useful Improvements in Hydrocarbon-Lamps, of which the following is a specification.

This invention relates to vapor lamps and 10 more especially to that type of lamp in which hydro-carbon is used in connection with the incandescent mantle.

It has for its principal object the provision of a lamp which will produce an illumination of the highest efficiency; the provision of means which will prevent the breakage of the shades used in connection therewith and also to provide an efficient construction whereby the removal of parts 20 to be cleaned may be simplified, and also to provide a construction whereby certain parts may be dis-assembled for convenience in packing.

Further objects of the invention are the 25 provision of means whereby the vaporizing structure may be conveniently pre-heated when it is desired to put the lamp in operation, these means being so constructed as to serve to hold the associated parts in 30 their proper position; the provision of means which will allow different size shades to be used in connection therewith and the provision of a lamp of this character which will be simple in operation, cheap of manufacture and efficient in operation.

The foregoing objects are obtained in the embodiment of the invention shown in the accompanying drawings, wherein like reference numerals designate similar parts of 40 reference throughout the various views and wherein Figure 1 is a side elevation of the upper part of the lamp, the shade being shown in section and the fluid reservoir being omitted; Fig. 2 is a central vertical 45 section through the operating parts; and Figs. 3 and 4 are sectional details on the lines 3 and 4 of Fig. 2.

The device comprises a reservoir, not shown, which serves as a base or standard 50 for the lamp and to which is secured a supply pipe 1 provided with a needle valve 2 whereby the flow of fluid may be controlled. The upper end of the needle valve casing is provided with a reduced threaded portion 55 3 which has applied to it a cup shaped nut

4, and this nut may be knurled about its periphery for convenience in applying and is provided with an annular recess 5 into which is placed an absorbent packing for a purpose to be hereinafter described. 60

The end 3 is provided with an internally threaded bore 6 into which is threaded a nipple 7 which is secured to the lower end of a vaporizing tube 8, this nipple is provided with a very fine bore 9 whereby 65 the vaporizing fluid is allowed to communicate with the interior of the tube 8, the tube 8 is packed with a quantity of asbestos thereby to break up the fluid into small particles and to equalize the pressure 70 supply to the mantles. The tube 8 is provided at its upper end with a cap 11 which may be threaded thereon and which is adapted to be slipped into a bore in the bottom of a cylindrical casting 12. The 75 cap 11 is provided at its top with a reduced bore 13 to allow the gas to pass upwardly through a pipe 14 where it is conducted through a manifold 15 and thence downwardly to the gas mantles 16 through the 80 pipes 17 and 18, the mantles being suspended upon the bottom of the pipes by the customary hangers 19. The cylindrical casting 12 is provided with a head 20 at one end and at the other end has threaded 85 therein a curved tube 21 whose end lies near to the interior of the shade 22, thus the casting 12 serves as a mixing chamber whereby the jet of gas is mixed with fresh air taken in from the remote end of the tube 21. 90 The foregoing is customary in this type of lamp and will require no further explanation.

The shade supporting structure comprises a horizontal plate 23 which is secured 95 at its central portion between a shoulder 27 formed upon the upper end of the needle valve casing and the nut 4 and has secured to its ends vertical rods or standards 25 which extend above the operating parts of 100 the lamp and support a similar shaped plate 26, which is rigidly secured by being clamped between the upper portion of the manifold 15 and the shoulder 27 formed upon the bottom of a rod 28 as shown particularly in Fig. 2, the rod 28 forming a convenient support for the arms of the shade supporting structure, this structure comprises a disk 29 which is vertically adjustable upon the rod 28 and is secured in a 110

fixed position by means of a set screw 30 threaded therein.

Spaced approximately 120 degrees apart and about the periphery of the disk 29 are 5 arms 31 which support the shade. These arms are secured to the disk 29 by having their ends threaded thereupon and extend outwardly to a point where they are bent at right angles to themselves then down- 10 wardly and outwardly to a point 33 where they are bent back upon themselves as at 34 and upwardly as at 35. By this partic- 15 ular construction I provide a means whereby the shade may be supported on the portions 34 and due to the fact that the wire or rod of which they are composed presents but a very slight contact between itself and the shade I allow the heat generated by the lamp to 20 reach all parts of the shade equally, provid- 25 ing thereby against unequal expansion and contraction of the shade. I also allow for shades provided with varying size openings at their tops to be applied to the supporting arms due to the resiliency of said arms.

25. It will be readily seen that shades of different depths may be supported upon this structure by adjusting the disk 29 with its associated parts vertically upon the post 28 as shown in dotted lines in Fig. 1 and the 30 top of the post 28 may have applied to it an ornamental structure 36 if desired. The 35 particular point of this construction per- tains to the pre-heating arrangement for the vaporizing tube 8, and the fact that this ar- rangement is utilized for locking the parts in an assembled condition upon receipt thereof from the shipper.

By first saturating the absorbent material in the cup 5 with a volatile fluid and igniting the same, the flames and heat thereof are caused to thoroughly heat the vaporizing tube thus generating sufficient gas to 40 ignite the mantles whereupon the heat generated by the mantles is sufficient to keep

the vaporizing tube heated during the burn- 45 ing of the lamp.

I claim:

1. In a lamp, the combination of a supply pipe and valve, an upright vaporizing tube communicating therewith and supported 50 thereby, a starting cup screwed on the upper end of the valve casing, below the tube, and a shade-supporting structure supported by the pipe and casing and including a cross plate clamped to said casing by said cup. 55

2. In a lamp, the combination of an oil supply valve casing having a nipple at its upper end threaded internally and externally, a shade support including a cross plate fitting on said nipple, a starting cup 60 screwed on the nipple and clamping said plate to the casing, and a vaporizing tube screwed into the nipple and projecting above the cup.

3. In a lamp, the combination of a valved 65 supply pipe, an upright vaporizing tube communicating therewith, a mixing tube having a slip connection with the upper end of the vaporizing tube, a manifold connected to the upper end of the vaporizing tube, 70 and a supporting structure for the mixing tube and manifold, including a lower cross plate mounted on the supply pipe, an upper cross plate fastened to the manifold, and rods connecting the plates. 75

4. In a lamp, the combination with a manifold and mantle tubes depending therefrom, a support for said manifold, a rod projecting upwardly from said support, and a shade holder adjustably mounted on 80 said rod.

In testimony whereof, I do affix my signature in presence of two witnesses.

FERDINAND A. RAFFEL.

Witnesses:

JOSEPH M. SANDS,
JOHN A. BOMMHARDT.
